HAIR CURLER

Gladys M. McIlrath, Racine, Wis.

Application August 16, 1949, Serial No. 110,495

9 Claims. (Cl. 132—33)

1

This invention relates to a hair curler.

It is a primary object of the invention to provide a one-piece spring and guard of such construction as to preclude catching of the hair in the angle between the spring and guard. As will be explained more fully hereinafter, this advantage is achieved by offsetting the curve of the guard from that of the spring to substantially eliminate any angle in which the hair may catch.

It is a further object of the invention to provide means whereby a single screw connects the winding arm to the handle and connects the handle to the mandrel in one operation.

In the drawings:

Fig. 1 is an enlarged view in perspective of a hair curling appliance embodying the invention.

Fig. 2 a view of the appliance in axial section.

Fig. 3 is a view taken in transverse section on the line 3—3 of Fig. 2.

The improved curler comprises a forming bar or mandrel 5, which, solely for reduction in weight, is desirably made with a cavity at 6. Externally, the bar is entirely cylindrical except for an annular channel at 7 which receives a screw 8 for rotatively positioning the knob 9 on the closed end of the bar. It will be noted that the knob 9 has a radial bore 10 which is bigger than the threaded shank of screw 8 and is counterbored at 11 to receive the head of the screw. The knob has a socket at 12 for the end of the mandrel and a recess 13 as best shown in Fig. 3 which is arcuate and opens into the socket 12 and receives the end of the spring arm 15. This arm is desirably arcuate in cross section to conform to the outer surface of the mandrel. It is desirably tapped so that the screw 8 is threaded therein. Since such screw is not in threaded connection with the knob, the tightening of the screw draws the arm 15 snugly against the interior surface of the knob. At the same time, the inwardly projecting end of the screw penetrates the annular channel 7 of the mandrel to anchor the knob rotatably on the mandrel.

That portion of the spring arm 15, which is arcuate in cross section, terminates at a transverse shoulder 16. This anchored portion of the arm 15 is precluded by its transverse section from substantial flexing during use. Beyond the shoulder, the arm portion 17 is relatively flat and highly flexible. At 18, its side marginal portions are folded back to provide a spring clamping lever 19 with a handle 20 connected to the end of the lever by a reversely curved offset at 21, such offset being normally in engagement with the arm portion 17 in proximity to the shoulder 16.

While the side portions of the arm are folded backwardly upon themselves to provide the lever 19, a central tongue 22, struck from the center of the blank from which the piece is formed, con-

2

tinues longitudinally of the mandrel 5 beyond the reversely turned bends 18. The tongue 22 is also reversely bent at 23, but desirably on a curve of larger radius than that which provides the bends at 18. Thus, the reversely extending guard 24 at the end of this tongue is spaced outwardly from lever 19. The fact that the bends at 18 and 23 are offset longitudinally of the mandrel, and the consequent disposition of the guard 24 outside of the bends at 18 makes it virtually impossible for hair to catch in the appliance during use.

Without the guard member 24, locks and strands of hair other than those upon which the curler is operating tend to become entangled with the forming lever 19 or with the lock of hair engaged by such lever, with the result that the rotative movement of the former and knob is arrested, and pain may be caused to the patient. The guard 24 deflects all hair other than that upon which the forming lever 19 is operative, thereby enabling the one lock of hair engaged by lever 19 to be wound smoothly upon the mandrel.

The use of the appliance is well understood, since the device differs only in the respects above noted from other hair curling devices. With the open end of the mandrel held against the scalp of the person whose hair is to be curled, a lock of hair is introduced beneath the clamping lever 19 by manipulating the hair under the offset provided at 21 near the free end of the lever. The oblique position of the handle 20 assists in guiding the hair under the offset and into the space between the lever 19 and the spring arm 17.

With the hair thus initially caught between lever 19 and the portion 17 of spring arm 15, the knob 9 is used to rotate the arm around the mandrel. This winds the lock of hair on the mandrel, the hair slipping through the space between lever 19 and portion 17 of the arm as the winding progresses. Ultimately, all of the hair will be wound directly on the mandrel and beneath the portion 17 of arm 15. As soon as the curl is thus formed on the mandrel, it is slipped axially down the mandrel from beneath the spring arm 15 and its coils are anchored to each other by a bobby pin or other suitable means.

Manufacture of the item is greatly facilitated by the fact that a single screw connects the three separate parts to each other in a single operation. In use, the danger of hair pulling is eliminated by the extension of the tongue portion 22 beyond the curve 18 before the tongue is bent at 23 to provide the guard 24.

I claim:

1. A hair curler comprising a mandrel and a part provided with a rotatable mounting on said mandrel and integrally including a spring arm portion and a guard portion, each of said por-

tions being reversely bent upon itself, the reverse bend of the guard portion being offset longitudinally of the mandrel beyond the reverse bend of the spring arm portion, and said guard portion including a terminal part extending back over the spring arm portion in partial lapping relation thereto.

2. As a new article of manufacture, a one-piece spring arm and guard for a hair curler comprising a strip having a longitudinally extending tongue struck from a portion of the strip intermediate its sides and ends, side portions of said strip being reversely bent upon themselves at the base of the tongue and the said tongue continuing beyond the reverse bend of said side portions and having a reverse bend of its own at a point offset from the bend of said side portions, and further having a terminal portion extending longitudinally of the strip in spaced relation to the side portions thereof.

3. The device of claim 2 in which the reverse bend of the tongue is of larger radius than the reverse bend of said side portions.

4. As a new article of manufacture, a combination spring arm and guard member for use in a hair curler, said member comprising a strip having a substantially rectilinear portion and having beyond said portion an elongated slot intermediate its side portions and ends, each of said side portions being provided with a reverse bend at one end of said slot and thence extending in substantial parallelism and in spaced relation to the substantially rectilinear portion of the strip, said strip having an integral tongue extending from its said rectilinear portion at one end of the slot beyond said bends, said tongue being provided with a reverse bend and a terminal guard portion spaced outwardly from the rectilinear portion and side portions of said strip and extending longitudinally of the strip in a rearward direction from the reverse bend of said tongue.

5. The device of claim 4 in combination with a mandrel along which said strip extends and a knob rotatable upon the mandrel and provided with a screw connecting the knob with said strip for the rotation of its said rectilinear portion about the mandrel, the said strip having a terminal with a tapped opening in which said screw is threaded.

6. The combination with a mandrel having an annular channel near one end, of a knob having a socket in which the channeled end of the mandrel is disposed, said knob having a recess opening into said socket and a substantially radial hole opening into the recess, a spring arm extending longitudinally of the mandrel and having an anchorage portion in the recess between the mandrel and the knob, said anchorage portion being provided with a tapped hole, and an anchorage screw extending through the radial hole of the knob into the tapped hole of the anchorage portion of said spring arm and in threaded connection with said arm, said screw having a terminal portion projecting beyond said arm into the channel of the mandrel for rotatably positioning the knob on the mandrel.

7. A hair curling device comprising a mandrel, a collar member rotatably mounted at one end of the mandrel, a winding member fixed to the collar member, said winding member comprising an arm member secured at one end to the collar member and extending parallel to the mandrel

and reversely bent at its free end to provide a guard member, the said arm member being provided intermediate its ends with a spring clip member integral at one end with the arm member at a point adjacent the guard member and extending in parallel and spaced relation to the arm member to provide a hair receiving opening, the free end portion of the spring clip member being provided with a reversely curved offset portion which resiliently engages the arm member whereby a tress of hair may be removably received between the arm and clip members.

8. In a hair curler of the character described comprising in combination, an elongated generally circular in cross section barrel, a groove in said barrel around the circumference and near one end thereof, a relatively short sleeve rotatably mounted on the barrel and extending over said groove, a tuft of hair engaging member comprising an elongated thin flat member having spring characteristics and extending to within a short distance of the other end of the barrel and lying parallel to and substantially on the barrel, said collar having a keyway with a depth and width adapted to snugly receive one end of said hair engaging member, a hole in said collar in alignment with said keyway, a hole in one end of said hair engaging member in alignment with the hole in the collar, a pin adapted to be held tightly in the hole in the collar and extending through the hole in said engaging means and into said groove, said engaging member comprising a single strip of flat material and lying generally longitudinally in contact with the barrel and extending to within a short distance from the other end of the barrel, the remainder of the strip being split into two elements, an end of one element being cut free at one end a distance from the free end of the strip and being curved outwardly at its other end and toward the end of the strip, the other element being curved at a smaller radius and extended parallel to the base for a distance toward said collar and then being curved for contact with the base member forming an opening and then being extended outwardly at an acute angle forming an entrance way into said opening, whereby the tuft of hair may be inserted into said opening and wound around the barrel until all of the tuft of hair is formed into a curl and positioned under said base member.

9. As a new article of manufacture, a one-piece spring arm and guard for a hair curler comprising a strip having a longitudinally extending tongue struck from a portion of the strip intermediate its sides and ends, side portions of said strip being reversely bent upon themselves at the base of the tongue and the said tongue continuing beyond the reverse bend of said side portions and having a reverse bend of its own at a point offset from the bend of said side portions.
